UNITED STATES PATENT OFFICE.

CLARENCE E. GUTHRIDGE, OF PITTSBURG, PENNSYLVANIA, ASSIGNOR TO OLIVER IRON AND STEEL COMPANY, A CORPORATION OF PENNSYLVANIA.

RAIL-STAY.

No. 867,359.

Specification of Letters Patent.

Patented Oct. 1, 1907.

Application filed December 26, 1906. Serial No. 349,376.

To all whom it may concern:

Be it known that I, CLARENCE E. GUTHRIDGE, a resident of Pittsburgh, in the county of Allegheny and State of Pennsylvania, have invented a new and useful Improvement in Rail-Stays; and I do hereby declare the following to be a full, clear, and exact description thereof.

My invention relates to a rail stay or anti-rail creeper, its object being to provide a simple yet effective device 10 of this character which may be readily formed from wrought metal if desired.

To these ends my invention comprises, generally stated, a rail stay comprising a bar adapted to extend across the bottom of the rail base, said bar having at one 15 end a clip formed integral therewith adapted to engage the flange of the rail at one side, the opposite end of said bar having an abrupt downwardly projecting portion, and a removable clip adapted to engage the opposite flange of the rail, said clip having a downwardly projecting portion and means for connecting the downwardly projecting portion of the bar and said removable clip.

In the accompanying drawings Figure 1 is a side view of a portion of a railway track showing my invention 25 applied thereto; Fig. 2 is a plan view of same; Fig. 3 is a cross-section; Fig. 4 is a perspective view of the separate portions of the rail stay; Figs. 5 and 6 show a modified form of my invention.

Referring to the accompanying drawing the numeral 30 2 designates a rail supported in the ordinary manner upon the ties 3 by means of spikes 4. The rail stay 6 comprises the bar 7 which may be formed of wrought metal extending across the under side of the rail base, said bar having the clip 8 adapted to engage the flange 35 of the rail on one side of said rail. At the opposite end of the bar 7 is the downwardly projecting portion 9 with the oblong opening 10 formed therein. The downwardly projecting portion 9 is slightly curved or bowed at 9^a, as indicated, for the purpose hereinafter set forth. Engaging the opposite flange of the rail 2 is the movable 40 clip 11 which has the downwardly projecting portion 12 with an opening 13 coinciding with the opening 10 in the portion 9. The bolt 15 is adapted to clamp the movable clip 11 to the portion 9, said bolt having the 45 oblong neck 16 just below its head, which oblong neck is adapted to engage the oblong opening 10 in the portion 9, whereby the bolt is held from turning when the nut 17 is applied thereto. It will be apparent that owing to the curved portion 9^a of the portion 9 the downwardly 50 projecting portion 12 of the clip 11 will engage only two points of the flange 9, leaving a space between

said portion 9 and the downwardly projecting portion 12 of the clip 11. As a consequence when the nut 17 is tightened there will be a certain spring or resiliency between the two parts, which will act to lock the nut 17 55 and prevent its loosening on the bolt. This spring or resiliency will tend to take up any wear which would tend to loosen the clip 11, and act to still hold said clip securely in place.

As the portions 9 and 12 extend down from the bar 7 60 at one end thereof and bear against the face of the tie to prevent the movement of the rail-stay in that direction, it will be apparent that any pressure tending to force said portions against the tie will also act to slightly twist the opposite end of the rail stay and so act to bind 65 the rail tighter and prevent its liability of slipping or creeping.

In Figs. 5 and 6 I have illustrated a modified form of my invention in which there is a depending flange 18 bearing against the inner face of the tie and acting to 70 prevent the movement of the rail.

What I claim is:

1. In a rail stay, a bar extending substantially across the lower face of the rail having a clip at one end thereof adapted to engage the flange of the rail, and an abruptly 75 downwardly projecting portion at the opposite end of said bar, a movable clip adapted to engage the flange of the rail, and means for securing said clip to said downwardly projecting portion of said bar.

2. In a rail stay, a bar adapted to extend substantially across the bottom of the rail having a clip at one end thereof and an abruptly downwardly projecting portion at the opposite end, a movable clip adapted to engage the flange of the rail and having a downwardly projecting portion, and means for securing the downwardly projecting portion of said clip and the downwardly projecting portion of said bar together. 80

3. In a rail stay, a bar extending substantially across the bottom of the rail having a clip at one end adapted to engage the flange of the rail and having an abruptly 90 downwardly projecting portion at the opposite end, a movable clip adapted to engage the flange of the rail and having a downwardly projecting portion, and a bolt passing through the downwardly projecting portion of said clip and the downwardly projecting portion of said bar. 95

4. In a rail stay, a bar adapted to extend across the bottom of the rail having a clip at one end thereof adapted to engage the flange of the rail and a downwardly extending curved portion at the opposite end, a movable clip adapted to engage the flange of the rail and having a downwardly projecting portion, and a bolt passing through said downwardly projecting curved portion of said bar and the downwardly projecting portion of said movable clip. 100

In testimony whereof, I, the said CLARENCE E. GUTHRIDGE, have hereunto set my hand.

CLARENCE E. GUTHRIDGE.
